UNITED STATES PATENT OFFICE.

VINCENZO BENEDETTI, OF PALISADE, NEW JERSEY.

DESIGN FOR A SHOE.

60,008.

Specification for Design.

Patented Dec. 20, 1921.

Application filed September 28, 1921. Serial No. 503,985. Term of patent 3½ years.

To all whom it may concern:

Be it known that I, VINCENZO BENEDETTI, a citizen of the United States, residing at Palisade, in the county of Bergen and State of New Jersey, have invented a new, original, and ornamental Design for Shoes, of which the following is a specification, reference being had to the accompanying drawings, forming part thereof.

In the drawings:

Fig. 2 is a side view of the same.

I claim:

The ornamental design for a shoe, as shown.

VINCENZO BENEDETTI.
